UNITED STATES PATENT OFFICE.

FRANCIS M. BARTON, OF CHICAGO, ILLINOIS, ASSIGNOR TO BARTON SPIDER-WEB SYSTEM, OF CHICAGO, ILLINOIS, A CORPORATION OF ILLINOIS.

CONCRETE-STEEL CONSTRUCTION.

Application filed December 3, 1925. Serial No. 72,858.

The invention relates to concrete steel construction. In steel reinforcement for beams, it is now common practice to provide a series of stirrups to support the reinforcing rods which extend longitudinally of the beam. In some instances, the stirrups are independent of one another, and in other instances a series of them are connected by bars rigidly secured thereto. The latter construction has the advantage of being placed in position as a unit in the form. A disadvantage incident to the unit constructions is that they are bulky in handling and transportation.

The primary object of the present invention is to provide a unit comprising a series of stirrups which are connected together by bars extending longitudinally of the beam which may be folded for convenience in handling and to reduce their bulk in transportation. This object is attained by providing a structure in which the legs of a series of stirrups are pivotally connected to longitudinally extending bars in such manner that the bars and legs may be brought together in compact relation until they have been brought to the concrete-form for installation in a beam. Another object is to provide improved spacing and supporting lugs for the stirrup.

The invention consists in the several novel features hereinafter set forth and more particularly defined by claims at the conclusion hereof.

In the drawings: Fig. 1 is a perspective of a structure embodying the invention, the members thereof being spread apart for installation. Fig. 2 is an inverted plan, showing the structure in its folded or compacted position. Fig. 2^a is a perspective of one of the lugs or feet for supporting the stirrups. Fig. 2^b is an elevation of said bracket with the stirrup therein. Fig. 3 is a section, showing the structures in operative position. Fig. 4 is a detail, showing the deformation in the legs of the stirrups for holding them against longitudinal movement with respect to the connecting bars. Figs. 5 and 6 are details, showing the connection between the stirrup legs and the connecting bars. Figs. 7 and 8 are details, showing the manner of notching the bar to receive the stirrup legs and the deformation of the bar to pivotally connect the legs and the bar.

The invention is exemplified in a structure comprising a series of stirrups formed of

steel rods each comprising legs 10 and 11, a bottom cross member 12 and out-turned terminals 13 at the upper ends of the legs, all of said parts being integrally formed. Some of the stirrups are provided with downwardly and outwardly extending lugs or feet 14 adapted to rest in the corners at the bottom of the concrete-form in which the concrete beam is cast, to space the member 12 the desired distance from the bottom of the beam, so as to space and support reinforcing rods 16 which extend longitudinally of the beam above the bottom of the beam, as well understood in the art. The out-turned ends 13 are adapted to extend into the floor slab contiguous to the beam, leaving the tops of the stirrups open so the rods 16 can be placed from above onto the cross-members 12 of the stirrups. The legs 11 of the stirrups extend through holes 17 respectively in a bar 18. This bar thus connects all of the legs 11 at one side of the entire series of stirrups. In fabricating the unit, holes 17 are open at one side, as shown in Fig. 7, to permit the legs to be slipped into them, and after they have been placed therein, the metal adjacent the sides of the open end of the hole is bent inwardly, as at 19, to prevent separation of the legs from the bar while permitting relative rotation between the bar and the legs. To hold the bars 18 against relative vertical displacement with respect to the stirrup legs, each lug is cut and deformed, as at 20, to form lugs above and below the bar between which the bar will be vertically confined. The legs 10 of the entire series of stirrups at the opposite side are similarly connected by a lower longitudinally extending bar 21 and an upper longitudinally extending bar 22. These bars 21 and 22 serve to space the stirrup legs 10, and are pivotally connected to said legs by holes 17 and indented portions 19 as aforesaid, and are confined against vertical movement on the legs by lugs 20. To space the upper portions of the stirrup-legs and the connecting bars inwardly of the sides of the beam, each of said bars is formed with outstruck portions 23 in any desired number, the outer edges of these portions being adapted to engage the sides 15^a of the form used in casting the concrete of the beam. The bars 18, 21 and 22 serve as longitudinal reinforcing bars for the concrete beam, as well as spacing elements for the stirrups.

The stirrups and bars, to which they are pivotally connected, are fabricated as a unit, and this is usually done in the shop where the reinforcement is made. When a unit has 5 been assembled, it may be folded together, as shown in Fig. 2, so that a large number of units may be shipped in a comparatively small space, the pivotal connections between the stirrup legs and the bars making this 10 possible. When the unit is to be installed, it is only necessary to spread the bars 18 from the bars 21, 22 into the position shown in Fig. 1 and place it as a unitary structure in the form, so that no individual placing 15 of the stirrups will be necessary. A further characteristic of the unit is that it is adapted for beams of different widths, because the pivotal connections between the bars and the stirrup legs permit the legs on one side to be swung towards the other side a greater or less distance if the unit is to be used in a beam of somewhat less width than the maximum for which it is adapted when the legs are spread to the fullest degree.

25. In practice, it has been found that a plurality of bars connecting the stirrup legs at one side and a single bar connecting the stirrup legs at the other side are sufficient to keep the stirrups properly spaced. The 30 single bar is vertically offset with respect to the plurality of bars so that the inner edges of the bars can be brought into engagement with the stirrup legs on the opposite side of the stirrups, so that the legs at one side will be brought approximately into alignment with the legs at the other side.

Each lug 14 is formed of a single piece of sheet metal shaped to form a recess 30 conforming to one side of the lower corners of the stirrups, so that the leg, when seated in said recess, will be positioned against vertical and rotative movement, and with outward and downward extensions 31, which are of the desired length and shape to position the bottom members 23 of the stirrups above the bottom of the form and to position the stirrup legs inwardly of the sides of the beam-forming portions of the concrete-form and with tongues 32, 33 and 34 which are integral with the lugs and adapted to be bent around the other side of the stirrup to rigidly secure the lug thereto. Tongues 32 and 33 are normally spread into open position, as shown in Fig. 2^a, and are bent into the position shown in Fig. 3 after the corner of the stirrup has been seated in the recess 30 of the lug. Tongue 34 is struck up from the metal in the extension 31 and serves, in conjunction with the other lugs, to rigidly secure the lug to a stirrup. In practice, these lugs may be applied at the place of installation of the reinforcement, and by providing lugs of different heights or dimensions, the same reinforcing structure 60 may be differently positioned in the form.

By attaching the lugs to the lower corners of the stirrups, they serve to support the stirrup vertically, as well as to hold it against lateral movement. This lug exemplifies one which can be produced at a low 70 cost and can be quickly attached to the stirrups.

The invention exemplifies a unit for concrete steel construction in which individually formed stirrups comprising legs and 75 cross members are connected together so they may be unitarily handled, and which can be folded into a substantially flat structure for convenience in shipment and handling prior to the installation or placement so in the forms.

The invention is not to be understood as restricted to the details set forth, since these may be modified within the scope of the appended claims, without departing from the 85 spirit and scope of the invention.

Having thus described the invention, what I claim as new and desire to secure by Letters Patent, is:

1. In reinforced concrete construction, the combination of a series of individually formed stirrups, each of said stirrups comprising legs and a cross member adapted to support reinforcing rods, and bars through which extend the legs at the sides of the 95 stirrups respectively and in which they are pivoted to permit the structure to be collapsed laterally to bring the legs at one side approximately into alignment with the legs at the other side.

100 2. In reinforced concrete construction, the combination of a series of individually formed stirrups, each of said stirrups comprising legs and a cross member adapted to support reinforcing rods, and bars connecting the legs at the sides of the stirrups respectively and in which said legs are pivoted to permit the structure to be collapsed to bring the legs at one side approximately into alignment with the legs at the other side, 110 the legs having integral means to retain the base against movement lengthwise of the legs.

115 3. In reinforced concrete construction, the combination of a series of individually formed stirrups, each of said stirrups comprising legs and a cross member adapted to support reinforcing rods, and bars connecting the legs at the sides of the stirrups respectively and in which they are pivoted to permit the structure to be collapsed to bring the legs at one side approximately into alignment with the legs at the other side, the bars having open-ended slots through which the legs are extended and deformed portions to 120 retain the legs in the slots, the legs having integral lugs to retain the bars against movement lengthwise of the legs.

125 4. In reinforced concrete construction, the combination of a series of individually 130

- formed stirrups, each of said stirrups comprising legs and a cross member adapted to support reinforcing rods, and bars connecting the legs at the sides of the stirrups respectively and in which they are pivoted to permit the structure to be collapsed to bring the legs at one side approximately into alignment with the legs at the other side, the bars being provided with means to space them from the sides of the form for the concrete. 45
5. In reinforced concrete construction, the combination of a series of individually formed stirrups, each of said stirrups comprising legs and a lower cross member adapted to support reinforcing rods, bars connecting the legs at the sides of the stirrups respectively, and spacing and supporting lugs, each formed of a single piece of flexible metal provided with a recess for a portion of 50 the stirrup and integral tongues adapted to be bent around the structure to secure the lug and stirrup together. 55
6. In reinforced concrete construction, the combination of a series of individually formed stirrups, each of said stirrups comprising legs and a lower cross member adapted to support reinforcing rods, bars connecting the legs at the sides of the stirrups respectively, and spacing and supporting lugs, each formed of sheet metal and with a recess to receive a corner of a stirrup between a leg and a cross member, and an integral tongue adapted to be bent around said corner to secure the lug and stirrup together. 60
7. In reinforced concrete construction, the combination of a series of individually formed stirrups, each of said stirrups comprising vertically extending legs and a lower cross member adapted to support reinforce- 65
- ing rods, and bars connecting the legs at the sides of the stirrups respectively, the bars being provided with integral outtruck portions to space them from the sides of the form for the concrete. 70
8. In reinforcement for concrete construction, the combination of a series of individually formed stirrups, each of said stirrups comprising a pair of legs and a cross member extending between the lower ends of the legs and adapted to support reinforcing rods, and a pair of longitudinal members at the sides of the stirrups respectively, said members having integral portions thereof forming sockets in which the legs are pivotally mounted so as to permit the unit to be collapsed so as to bring the legs at one side thereof approximately into alignment with the legs at the other side. 75
9. In reinforcement for concrete construction, the combination of a series of individually formed stirrups, each of said stirrups comprising a pair of legs and a cross member extending between the lower ends of the legs and adapted to support reinforcing rods, a pair of longitudinal members at the sides of the stirrups respectively, said members having integral portions thereof forming sockets in which the legs are pivotally mounted so as to permit the unit to be collapsed so as to bring the legs at one side thereof approximately into alignment with the legs at the other side, and legs on some of the stirrups adjacent the intersections of the lower ends of the legs and the ends of the cross-members, for spacing the unit from the bottom of the concrete form. 80
